ATTORNEYS,

UNITED STATES PATENT OFFICE.

LEBRECHT FRITZSCHE, OF NEWARK, NEW JERSEY.

DESIGN FOR A HANDLE FOR BUTTON-HOOKS OR SIMILAR ARTICLES.

SPECIFICATION forming part of Design No. 29,959, dated January 10, 1899.

Application filed December 12, 1898. Serial No. 699,079. Term of patent 3½ years.

To all whom it may concern:

Be it known that I, LEBRECHT FRITZSCHE, a citizen of the United States, residing at Newark, in the county of Essex and State of New Jersey, have invented and produced a new and original Design for Handles for Button-Hooks or Similar Articles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan view of a button-hook having a handle of my new design, and Fig. 2 is a central longitudinal section of the same on line *x*.

As shown in the drawings, the leading feature of my design consists in opposite pairs of conventionalized foliated scrolls outlining the edges of the smaller end of the handle of a button-hook or similar article, a series of scallops outlining the edges of the larger end, and an outwardly-curved scroll at the tip of the handle. From the smaller extremity of the handle long foliated scrolls *a a* extend along the opposite edges of the handle, slightly diverging toward the larger part of the handle, and having their ends curved inward, as at *a' a'*. Adjacent to said inwardly-curved ends *a' a'* are opposite short scrolls *b b*, having their convexities turned outward and bordering a central open field *c*. Between the adjacent ends of said long scrolls *a a* and short

scrolls *b b* the side of the handle is ornamented with conventionalized flowers, as at *d*, which also extend between the long scrolls *a a* toward the small end of the handle. Next in order along the edges of the handle is displayed a pair of opposite outwardly-concave scrolls *e e*, diverging toward the larger end of the handle, and between the contiguous ends of the pair of outwardly-convex scrolls *b b* and the pair of inwardly-convex scrolls *e e* a cluster *f* of conventionalized floral ornaments is displayed on the side of the handle. Beyond the pair of inwardly-convex scrolls *e e* the opposite outwardly-curved edges of the larger end of the handle are outlined by opposite series *g g* of scallop-shaped ornaments, between which is a centrally-raised open field *h*, bordered by foliated scrolls *i i* adjacent to the series of scallops. Said series of scallops converge and closely approach at the end of the handle, a group *j* of floral ornaments being displayed between the approaching ends and a small scroll *k* at the tip of the handle.

What I claim as new is—

The design for a handle for button-hooks and similar articles, as herein shown and described.

In testimony that I claim the foregoing I have hereunto set my hand this 3d day of December, 1898.

LEBRECHT FRITZSCHE.
